UNITED STATES PATENT OFFICE.

HARRY H. GOODSELL, OF VANDERGRIFT, PENNSYLVANIA.

ANNEALING BOX.

1,421,212.

Specification of Letters Patent. Patented June 27, 1922.

Application filed September 22, 1921. Serial No. 502,426.

To all whom it may concern:

Be it known that I, HARRY H. GOODSELL, a citizen of the United States, and resident of Vandergrift, in the county of Westmoreland and State of Pennsylvania, have invented certain new and useful Improvements in Annealing Boxes, of which the following is a specification.

This invention relates to the construction 10 of annealing boxes of the cast type that are used in box annealing rolled steel sheets and plates and similar materials. The invention, although not limited thereto, more particularly relates to integrally cast annealing 15 boxes made of steel or alloys of steel.

Annealing boxes of this class comprise integral sides, ends and top, the lower side being open. The annealing box is fitted or placed on the upper face of a separate bottom, to close the bottom side of the box, the material annealed also resting on or being supported by the bottom during the annealing operations.

In box annealing rolled steel sheets and 25 plates and similar materials, a quantity of the materials is piled on the upper face of the annealing box bottom. The box, which in effect is simply a cover, is then lowered over the pile of materials until its lower 30 edges rest upon the box bottom. The joint between the lower edges of the annealing box and upper face of the annealing box bottom is then sealed from without with a small quantity of finely divided refractory 35 material, such as sand, fire clay or the like, so as to prevent ingress of the highly heated gases during the heating, or of air during the cooling operation.

The loaded annealing boxes are placed 40 within a suitable annealing furnace and heated therein. After being heated to the necessary temperature for the requisite time interval, the annealing box is removed from the furnace and allowed to cool, usually until 45 the contents of the box are at such low temperature as will avoid oxidation thereof when exposed to the atmosphere. When sufficiently cooled the annealing box or cover is removed from the bottom, so as to expose 50 the annealed materials. The materials will then be removed in the usual manner.

As annealing boxes of this class alternately are heated to a high temperature and cooled and the intense long continued heating 55 always being followed by cooling, the annealing boxes gradually warp and bulge or

crack and become otherwise distorted. Warping or bulging and cracking of the boxes is found most troublesome in the side walls of the annealing boxes, owing to the greater size or area of the side walls in comparison with the size of its ends or top, and the open lower side or bottom of the casting forming the box lends to the bulging and distortion at and near the lower edges of the boxes. The result is that the boxes rapidly deteriorate and soon become useless in further annealing operations.

Various ways have been suggested and used for strengthening the side walls of the annealing boxes, in efforts to increase the life of the boxes and lessen the expense connected with the operation of box annealing. In some cases a series of long vertical ribs or of long horizontal ribs, and in other cases, 75 a series of long ribs, both vertical and horizontal, have been employed. In other cases a series of long radial ribs, which converge at about the middle of the length and height of the sides of the annealing boxes, have 80 been used, but in so far as I am aware these various expedients have been only partly successful, and, prior to my invention, no entirely satisfactory means have been known or used for preventing or overcoming warping or bulging, cracking and similar distortions of the annealing boxes.

My invention consists in the provision on the exterior surfaces of the annealing boxes of a series of integrally formed ribs or projections, of a size, form, proportions, and relative arrangement, which not only avoids and overcomes the usual cracking, warping or bulging or other distortion of the annealing boxes in the casting thereof, but in addition thereto also coats one rib with another to lessen and prevent warping and cracking of the boxes when afterward used in annealing, to the end that the life of such annealing boxes is greatly extended and the losses due to the production of defective castings, in making the annealing boxes is largely reduced and the cost of box annealing rolled steel sheets and plates and like materials is very materially lessened.

Referring now to the drawing, forming part of this specification, Figure 1 is a longitudinal side elevation, partly in section, showing an annealing box of the cast type having reinforcing ribs thereon of the novel size, proportions, and relative arrangement forming my invention.

Figure 2 is a sectional end elevation of the annealing box of Figure 1, the section being taken on the line II—II of Figure 1.

In the accompanying drawings the 5 numeral 1, in a general way, designates a cast annealing box embodying my invention, the annealing box preferably being made of steel. This box, which, as shown, is of a length greater and width less than 10 its height, is provided with the usual lifting hooks or lugs 2 on the ends thereof by which the box is handled, the size and weight of such boxes ordinarily being so great as to require a crane to manipulate them. The 15 box 1 is also provided with interior reinforcing truss members 3 to prevent downward sagging of the arched roof and consequent outward bulging of the side walls.

The annealing box 1 is provided on each 20 of its sides with a multiplicity of reinforcing ribs or projections which are of relatively short length, the ribs being arranged in a series of horizontal rows. In the lowermost row, formed of the ribs 4, and in the 25 uppermost row, formed of the ribs 5, the ribs extend vertically lengthwise. In the intermediate rows of ribs, the ribs 6 and 7 extend lengthwise at an angle of approximately 45 degrees to the horizontal and it 30 is to be noted that the ribs 6 extend lengthwise at an angle of 90 degrees to the ribs 7. It also will be seen in Figure 1 that the distance between the adjacent ends of any two ribs 6 or two ribs 7 is about the same 35 as the length of these ribs and that the ribs 6 and 7 are in staggered relation.

Because of this staggered relation, one of the ribs 7 extends lengthwise between the adjacent ends of two of the ribs 6, and one 40 of the ribs 6 extends lengthwise between two of the ribs 7, or else between the end of a rib 6 and a rib 4 or 5. This peculiar relative arrangement of the rib forms a novel and important feature of my invention, as 45 the distance between the ends of the two ribs in a single row is made approximately equal to the length of the ribs. The result obtained by this arrangement is that in the expansion and contraction of the annealing box, which occurs each time it is 50 used in an annealing operation, the tendency of any of the ribs, in expanding or contracting lengthwise, to bow or warp the side surface of the annealing box in a direction parallel with the length of such rib is counteracted and overcome by the simultaneous sidewise expansion or contraction 55 of the rib between the adjacent ends of any two ribs. By reference to Figure 1 it will 60 be seen that the joints between the ends of the ribs are uniformly broken and that a line drawn in any direction across the side walls of the box must pass through a plurality of these short reinforcing ribs or projections.

Although the intermediate rows of ribs 6 and 7 are shown arranged in perfect alignment, and spaced apart in rows a distance equal to the length or width, and the rows of ribs 4 and 5 are shown lengthwise vertical, it is to be understood that this relative arrangement of the rows and relative arrangement of ribs in each row may be varied somewhat without loss of function. The width and height relative to the length 75 of the ribs also may be varied and the individual ribs may be other than in exact alignment and it is to be understood that such changes have been considered and are possible arrangements under my invention. 80

The advantages of my invention, which will readily be seen by those skilled in the art, result in a strong and effective reinforcement of the walls of the annealing boxes against distortion in any direction. Owing 85 to their reduced length, the ribs are easier to cast than the long ribs heretofore employed, as they do not tend to crack and break away from the side walls, either when being cast or when used for annealing, as in 90 the case of continuous long ribs extending around the annealing box. Furthermore, the short form of ribs is not exposed to the severe stresses that are set up between a continuous band or rib and the wall of the box 95 by unequal expansion and contraction under the conditions of use.

The arrangement, shape, comparative length, and proportions of the reinforcing ribs referred to herein may be varied somewhat, the essential thing being to have a plurality of short ribs, disposed in staggered order, with intervening short ribs running across the lines of the first series, so that on any line drawn through the side of the 100 box a number of the reinforcing ribs will be cut.

I claim:

1. An annealing box having a plurality of 110 rows of lengthwise separated reinforcing ribs on the outer surfaces thereof, said ribs being arranged in staggered relation and the ribs in each row extending lengthwise at an angle to the length of the ribs in an adjacent row.

2. An annealing box having a plurality of 120 rows of lengthwise separated reinforcing ribs on the walls thereof, said ribs being arranged in staggered relation, and the ribs of one row extending lengthwise at right angles to the length of the ribs in an adjacent row.

3. An annealing box having a plurality of 125 rows of lengthwise separated reinforcing ribs on the outer surfaces thereof, said rows of ribs being arranged in lines crossing each other, with the ribs of one row lying within the space between the adjacent ends of the aligned ribs in another of said rows.

4. An annealing box comprising walls 130

- having projecting reinforcing ribs thereon, said ribs being arranged in a plurality of rows, and ribs of each row being in lengthwise alinement, with intervening spaces, 5 each row of alined ribs extending transversely lengthwise to the length of the alined ribs of another row.
5. An annealing box comprising walls having reinforcing ribs thereon, said ribs 10 being arranged in at least two rows, with the ribs of each row extending lengthwise in parallel lines, and separated in each line by intervening spaces, and with the ribs of one series lying within the spaces between 15 the lengthwise alined ribs of another row.
6. An annealing box formed of cast metal and having reinforcing ribs on the walls thereof, said ribs extending lengthwise in at least two diagonal rows, with the ribs of 20 each diagonal row lying in the same straight line and separated one from another by

spaces of approximately the same length as the length of the ribs, the ribs of one diagonal row lying within the space between the ends of alined ribs in another row.

7. An annealing box formed of cast metal and having reinforcing ribs on the walls thereof, said ribs extending lengthwise in at least two diagonal rows, with the ribs of each diagonal row lying in the same 30 straight line and separated one from another by spaces of approximately the same length, as the length of the ribs, the ribs of one diagonal row lying within the space between the ends of alined ribs in another 35 row and a row of lengthwise vertical ribs at the top and bottom of the walls of the annealing boxes.

In testimony whereof I have hereunto set my hand.

HARRY H. GOODSELL.
